UNITED STATES PATENT OFFICE.

JAMES SHAW, OF CHICAGO, ILLINOIS, ASSIGNOR TO H. S. MOTOR CO., OF CHICAGO, ILLINOIS.

INTERNAL-COMBUSTION ENGINE.

1,292,103.

Specification of Letters Patent. Patented Jan. 21, 1919.

Substitute for renewal application Serial No. 200,172, filed November 3, 1917. This application filed June 17, 1918. Serial No. 240,545.

To all whom it may concern:

Be it known that I, JAMES SHAW, a citizen of the United States of America, and a resident of Chicago, in the county of Cook, 5 State of Illinois, have invented certain new and useful Improvements in Internal-Combustion Engines, of which the following is a specification.

This invention relates to that type of multiple cylinder internal combustion engines, 10 which constitutes the subject matter of my prior Letters Patent No. 1,188,496 dated June 27th, 1916.

And the present improvement has for its 15 object to provide a simple and efficient structural formation of the rotary valve member of an engine of the above mentioned type, and with which the usual timing of the inlet, compression, explosion and exhaust 20 strokes of the individual pistons of the series of engine cylinders are attained in a ready and effective manner, all as will hereinafter more fully appear.

In the accompanying drawings;—

25 Figure 1, is a longitudinal sectional elevation of the upper portion of a four cylinder engine, to which the present improvement is applied.

Fig. 2, is a horizontal section of the 30 rotary valve member, detached.

Figs. 3, 4, 6, 7, 8 and 9, are detailed transverse sections on lines 3, 4, 6, 7, 8 and 9, respectively, Fig. 1.

Fig. 5, is an enlarged detail section on line 35 6, Fig. 1.

Similar reference numerals indicate like parts in the several views.

Referring to the drawings, 1, 2, 3, 4, designate the series of engine pistons moving 40 in their respective cylinders 5, 6, 7, 8, and as in my former Patent No. 1,188,496, said series of cylinders are preferably arranged in pairs and with each pair in separate relation as shown in Fig. 1. In said Fig. 1, 45 the reference numerals 1, 2, 3, 4 are applied to the series of engine pistons in the order in which they are timed for operation.

9 designates the valve housing common to the series of engine cylinders, and formed 50 with a series of inlet-outlet ports or passages 10, connecting the bore of said housing with the combustion chambers of the engine cylinders 5, 6, 7, 8; with a series of outlet or exhaust passages 11, in diametri-

cally alined relation to the aforesaid inlet-outlet passages 10, and adapted for intermittent registry therewith by the rotary valve number 13 hereinafter described, and with a gaseous fuel inlet port or passage 12, formed midway the length of the valve 60 housing and adjacent to the before described space which separates the pairs of engine cylinders 7, 5 and 8, 6. The said fuel inlet port or passage 12 opens into the bore of the valve housing 9, at one side of the 65 same, as shown in Fig. 3, and is adapted in the continued operation of the engine to have serial communication with the series of longitudinal sub-chambers or passages of the rotary valve member now to be described:

13 designates the valve member above referred to, of a length approximately the length of the bore of the valve housing 9 and having a turning fit therein. Said valve 75 is operatively connected to the main shaft of the engine by any usual intermediate speed reducing gearing, and receives rotation from said engine shaft at the ratio of one revolution of the valve to four revolutions of the 80 engine shaft.

14, 15 designate a pair of counterpart spirally arranged partitions disposed in alined relation within the circular outer shell of the valve member, and dividing the 85 same into a plurality of longitudinal sub-chambers or passages 16, 17, 18, 19, which have a spiral formation corresponding with that of the aforesaid spiral partitions 14, 15. Said sub-chambers are adapted to serially register with the fuel inlet port 12 aforesaid, and each sub-chamber will remain in register with said fuel inlet port 12 during a quarter revolution, approximately, 90 of the valve member 13.

In the present improvement, the shell of the rotary valve member 13, is provided with an X shaped partition 20, disposed intermediate of the spiral partitions 14, 15, above described, and the four longitudinal webs of said partition 20, are in turn formed with angularly disposed branches 21, arranged alternately at opposite ends of said longitudinal webs, as illustrated in Fig. 2. With the described arrangement of parts, 100 the partition 20, 21, provides a series of four receiving chambers 22, 23, 24, 25, which alternately open in opposite directions and 105

have individual communication with the series of sub-chambers or passage ways 16, 17, 18, 19, above described. Each of said receiving chambers 22, 23, 24, 25, has its individual inlet port or opening formed in the shell of the valve and adapted to serially register with the fuel inlet port 12 of the valve housing 9 during approximately a quarter revolution of the valve. Accordingly when one of said receiving chambers is in communication with said fuel inlet port, to supply fuel charges to an engine cylinder, the remaining receiving chambers are out of register and dormant.

15 26, 27, 28 and 29, designate a series of transverse passages or ducts extending diametrically through the valve member 13, with their walls forming portions of the spiral partitions 15, 16, aforesaid. The said 20 passages or ducts are disposed in spaced relation correspondingly with that of the series of inlet-outlet ports 10, of the engine combustion chambers and the companion series of outlet ports 11 of the valve housing 9, and with each of said passages or ducts 25 individual to companion ports 10 and 11 aforesaid.

30, 31, 32 and 33, designate quadruple pairs of ports or passages in the shell of the 30 rotary valve member 13, with each pair of said ports arranged in diametric relation to each other and individual to a pair of adjacent sub-chambers 16, 17, or 18, 19, heretofore described. Said pairs of ports 35 or passages 30, 31, 32, 33 are disposed in the same space relation as that above described in connection with the passages or ducts 26, 27, 28, 29 and each port of each pair of ports is adapted to register with the inlet- 40 outlet port 10 of its engine cylinder, once in each revolution of the rotary valve member 13.

In the present valve structure, the series 45 of transverse passages or ducts 26, 27, 28, 29, as well as the companion series of ports or passages 30, 31, 32, 33 are disposed in angular relation to each other in their direction of circular movement within the valve housing 9, and with each individual 50 set of passages, one-eighth of a circle, in advance of the next succeeding set of passages; said advance corresponding with the advance or twist of the partitions 14, 15, and the series of sub-chambers 16, 17, 18, 19.

55 With the above described association of parts, and with the first piston 3, Figs. 1 and 6, at the beginning of its explosion or power stroke, the transverse duct 28 and the passage 32 individual to the combustion 60 chamber of said piston 3, will be out of register with the inlet-outlet port 10 of said combustion chamber. At the same time the second piston 1, Figs. 1 and 7, is at the beginning of its fuel inlet or suction stroke, 65 with its transverse duct 26, out of register

with the inlet-outlet port 10 of the combustion chamber of said piston 1, and with one of the pair of passages 30 commencing to register with said inlet-outlet port 10. At the same time the third piston 4, Figs. 1 and 8, is at the beginning of its compression stroke, with the transverse duct 29 and passages 33 individual to the combustion chamber of said piston 4 out of register with the inlet-outlet port 10 of said combustion chamber. At the same time the fourth piston 2, Figs. 1 and 9, is at the beginning of its outlet- or exhaust stroke with the passages 31, out of register with the inlet-outlet port 10 of the combustion chamber of said piston 2, and with the transverse duct 27 commencing to register with said inlet-outlet port 10.

34 designate transverse grooves or channels, preferably two in number, as shown 85 more particularly in Fig. 5, and formed near the respective ends of an exhaust duct or flue of the rotary valve member 13. With the described structure formation, a free expansion and contraction of the metal 90 of the walls of said duct or flue, under the influence of the flashes of flame to which the same is exposed in actual use, can take place, and the usual buckling and warping 95 of said walls are effectively prevented.

Having thus fully described my said invention what I claim as new and desire to secure by Letters Patent, is:—

1. In combination, a plurality of cylinders and pistons common to a single engine 100 shaft, a valve housing common to the plurality of cylinders and having inlet-outlet ports communicating individually with the combustion chambers of said cylinders, the valve housing having a single inlet port for 105 gaseous fuel and a plurality of individual outlet ports, and a rotary valve member disposed longitudinally in said valve housing and comprising a partitioned shell providing pairs of longitudinal sub-chambers in 110 aligned relation and a quadruple series of receiving chambers intermediate of said sub-chambers and opening alternately into one and the other of said sub-chambers, each sub-chamber aforesaid having a pair of 115 ports adapted for serial registry with the inlet-outlet ports of a pair of engine cylinders, and said shell having a series of transverse ducts each individual to the inlet-outlet port of an engine cylinder and an outlet port of the valve housing, substantially as set forth.

2. In combination, a plurality of cylinders and pistons common to a single engine 125 shaft and having a centrally spaced relation, a valve housing common to the plurality of cylinders and having inlet-outlet ports communicating individually with the combustion chambers of said cylinders, said valve housing having a single inlet port 130

- adjacent to the central space between the aforesaid cylinders and a plurality of individual outlet ports, and a rotary valve member disposed longitudinally in said
- 5 valve housing and comprising a partitioned shell providing pairs of longitudinal sub-chambers in aligned relation and a quadruple series of receiving chambers intermediate of said sub-chambers and opening 35 alternately into one and the other of said sub-chambers, each sub-chamber having a pair of ports adapted for serial registry with the inlet-outlet ports of a pair of engine cylinders and said shell having a 40 series of transverse ducts each individual to the inlet-outlet port of an engine cylinder, and an outlet port of the valve housing, substantially as set forth.
- 10 3. In combination, duplicate series of cylinders and pistons common to a single engine shaft and having a centrally spaced relation, a valve housing common to the plurality of cylinders and having inlet-outlet ports communicating individually with
- 15 the combustion chambers of said cylinders, said valve housing having a single inlet port adjacent to the central space between the aforesaid cylinders and a plurality of individual outlet ports, and a rotary valve
- 20 member disposed longitudinally in said valve housing and comprising a partitioned
- 25 shell providing pairs of longitudinal sub-chambers in aligned relation and a quadruple series of receiving chambers intermediate of said sub-chambers and opening 35 alternately into one and the other of said sub-chambers, each sub-chamber having a pair of ports adapted for serial registry with the inlet-outlet ports of a pair of engine cylinders and said shell having a 40 series of transverse ducts each individual to the inlet-outlet port of an engine cylinder, and an outlet port of the valve housing, substantially as set forth.
- 30 4. In combination, a piston, a cylinder, a valve housing having a fuel inlet passage, an exhaust passage and an inlet-outlet passage communicating with the cylinder aforesaid, and a rotary valve arranged in said housing and comprising a partitioned shell providing sub-chambers adapted to serially register the fuel inlet passage with the inlet-outlet passage aforesaid, and a diametric duct adapted to register said inlet-outlet passage with the exhaust passage 55 aforesaid, the wall of said duct being formed with a transverse groove, substantially as set forth.

Signed at Chicago, Illinois this 14th day of June, 1918.

JAMES SHAW.
